CARD ROLLER MOUNTING MACHINE

Edward S. Flynn, Lowell, Mass., assignor to Davis & Furber Machine Company, North Andover, Mass., a corporation of Massachusetts

Application November 22, 1934, Serial No. 754,269

5 Claims. (CL. 140—99)

This invention relates to a machine for applying fillet material under tension to a driven roll and, while useful for a variety of purposes and for handling a variety of fillet material, is particularly designed for applying a fillet of card clothing to a cylinder such as a drum or roll employed in a carding machine.

The object of the invention is to provide such a machine in which the fillet material, while being wound on to the drum or roll, shall be automatically maintained under a predetermined and uniform tension.

In the case of card clothing, the desired tension is usually dependent upon the width of the fillet of card clothing, the diameter of the cylinder upon which it is being wound and the character of the card clothing itself. In the case of a fillet of card clothing, the desired tension which should be maintained is usually on the order of between one hundred and six hundred pounds.

The nature and objects of the invention will appear more fully from the accompanying description and drawings and will be particularly pointed out in the accompanying description and claims.

The preferred form of the invention is shown embodied in a well-known form of machine for winding a fillet of card clothing upon a cylinder, such, for example, as that shown in the patent to Dronsfield, No. 548,632, October 29, 1895.

In the drawings:

Fig. 1 is a view in perspective of the mounting machine with the preferred form of the present invention embodied therein.

Fig. 2 is a detail in top plan view illustrating the lever connection between the controller and the shiftable cam or wedge-shaped plate.

Fig. 3 is an end view of the construction shown in Fig. 2.

Fig. 4 is a side elevation of the machine shown in Fig. 1.

The fillet material illustrated is a fillet of card clothing of a familiar type comprising a backing strip 1 of suitable material such as leather or fabric and a series of wire teeth 2 inserted through the backing and projecting at the face thereof with the surface ends of the teeth uniformly inclined in the same direction.

Such a fillet of card clothing is wound upon the drum and various rolls of a carding machine and it is of prime importance that when in place it shall fit snugly and tightly the periphery of the drum or roll. In order to secure this result the fillet is maintained under a very substantial

degree of tension as it is being applied to the drum or roll. As already pointed out, this tension must be maintained uniform and the degree of tension must depend upon the particular requirements. In covering the drum and rolls of carding machines the desired tension maintained is on the order of from one hundred to six hundred pounds.

While various machines may be employed for winding or mounting such fillet material upon the cylinder such as the drum or roll of a carding machine, a well-known type of machine such as that shown in the Dronsfield patent above referred to is here illustrated. This machine comprises a base 3 mounted to move transversely along a bed 4. This bed may be mounted independently on a suitable support or may be mounted directly upon the frame of the carding or other machine. Usually the base is fed at the required rate transversely or longitudinally of the roll to be covered, as, for example, by the cooperative action of the screw 5 and worm wheel 6 with the worm wheel 6 being locked against rotation during the traversing movement and so acting as a nut. Vertical side plates 7 and 8 extend upward from the base 3 and there is journaled in these side plates the shaft 9 of a cone drum divided into three sections, 10, 11 and 12, of successively increased diameter.

The fillet material passes first over and around the drum section 10, thence over and around the drum section 11 and thence over and around the drum section 12. A curved plate (not shown in the drawings) at the front of the machine shunts the fillet from one section to the other. The third cone section 12 is usually covered with leather. From the bottom of the third cone section 12 the fillet then passes up over the top of a controller 13 in the form of a lever fulcrumed at 14 on the base 3. From the controller the fillet passes forward to the roll upon which the fillet is to be wound and this roll is positively driven or rotated by hand or otherwise.

It will thus be seen that as the fillet 1 is pulled forward by the roll upon which it is being mounted, it acts to rotate the cone drum, but as the cone section 12 is larger in diameter than the preceding cone sections, slippage must take place between the fillet and the preceding cone sections and this slippage produces the main tension in the fillet.

An additional amount of friction which is adjustable or under control is provided on the fillet before it passes to the cone drum. For that purpose a small bed plate 15 having the upturned

sides 16 forming a box of substantially the width of the fillet is mounted by means of the bracket 17 on the vertical side plate 7. The fillet before passing to the cone drum passes over this bed plate 15 with its back thereagainst. A flat top plate 18 rests in the box formed by the side plate 16 on top of the teeth of the fillet and is pressed downward to apply the required amount of friction.

- 10 Heretofore this friction has been manually controlled. In the present invention it is automatically controlled and for that purpose a shiftable cam preferably in the form of a wedge-shaped plate 19 is mounted on top of the top plate 18. 15 This wedge-shaped plate is thicker at the front of the machine and thinner at the rear. Its top surfaces rests against an abutment shown as a set screw 20 threaded into an arm 21 mounted upon one of the sides 16. It will thus be seen 20 that as the wedge-shaped plate or shiftable cam 19 is moved forward or rearward, the pressure applied to the fillet and consequently the retarding friction will be decreased or increased while the set screw 20 enables a manual adjustment to be made.

25 The pivotal controller 13 at its upper end is recessed to provide a guideway for the fillet and it is also provided with a guide roller 22 over which the fillet passes. The lower arm of this controller extends rearward and is connected by powerful springs 23 to the upper end of the side plate 8.

30 When the roll upon which the fillet is being wound is driven, the upper recessed end of the controller is drawn rearward by the tension on the fillet and the springs 23 press the controller against the fillet with a pressure just sufficient to be overcome by the desired tension on the fillet. In order to indicate the desired tension, a scale 35 40 is marked on the upper edge of the side plate 8 and a pointer 25 cooperating with this scale is pivoted at 26 on the side plate. A slotted arm 27 extending rearward from the pointer engages a stud 28 projecting from the lower arm of the controller lever through a slot 29 in the side plate. Consequently this pointer will indicate on the scale the amount of pressure exerted by the 45 springs 23 through the controller against the fillet and this scale is usually graduated to indicate in pounds the tension existing in the fillet as it is drawn through the machine over the controller against the retarding friction.

50 In the present invention means are provided connecting the controller and the retarding friction applying means, which connecting means act upon movement of the controller caused by a change from the desired tension to effect a compensating change in the retarding friction and thereby to restore the desired tension. A simple 55 and preferred form of means is illustrated in Figs. 2 and 3 and consists of a lever 30 fulcrumed at 31 on a bracket 32 projecting from the side 60 65 16. At one end this lever is slotted and engages a stud 33 projecting from the shiftable cam or wedge-shaped plate 19, while at the other end it is provided with spaced pins 34 between which projects a stud 35 projecting inward from the controller 13. Consequently any movement of the controller forward or rearward acts to shift the wedge-shaped plate 19 rearward or forward and thus to increase or decrease the retarding friction applied to the fillet.

70 If, then, the roll upon which the fillet is being wound is driven with the end of the fillet connected thereto, and it is desired to maintain a

75 tension of a desired amount indicated, for example, by the point 36 on the scale 24, the screw 20 is adjusted until the retarding friction applied to the fillet between the plates 18 and 15, together with the retarding friction applied by the cone drum, is such that the pointer stands at this point 36 on the scale. If, now, any change takes place in the desired tension, the controller will swing one way or the other on its pivot but immediately this swinging movement takes place in either direction the connection from the controller to the cam 19 acts to shift the cam in a direction to effect a compensating change in the retarding friction and thus bring the pointer back to the point 36 and thus restore the desired tension. 10 15

The invention thus acts automatically to maintain constant any desired uniform tension in the fillet.

Not only does the invention compensate for any changes which take place in the pull exerted 20 by the rotation of the driven roll to which the fillet is being applied, but it also compensates for the slight variations which may occur in the overall thickness of the fillet as it passes between the plates 18 and 15 and which, if not compensated 25 for, would change the amount of retarding friction applied to the fillet.

Having thus described the invention, what is claimed as new, and desired to be secured by Letters Patent, is:

and means connecting the controller and the shiftable cam acting upon movement of the controller caused by a change from the desired tension to shift the cam in the direction to effect a compensating change in the retarding friction and thereby to restore the desired tension.

4. An apparatus for applying fillet material under tension to a driven roll comprising means for applying a retarding friction to the fillet including a bed plate over which one face of the fillet is drawn by the driven roll, an abutment opposite the bed plate, and a shiftable cam between the abutment and the other face of the fillet acting when shifted to change the amount of retarding friction applied to the fillet; a pivotally mounted controller engaging the fillet between the driven roll and the retarding friction-applying means; a spring connected to the controller

and acting to press the controller against the fillet with a pressure just sufficient to be overcome by the desired tension on the fillet; and a lever fulcrumed between and connected at its ends respectively to the controller and the shiftable cam acting upon a pivotal movement of the controller caused by a change from the desired tension to shift the cam in a direction to effect the compensating change in the retarding friction and thereby to restore the desired tension.

5. An apparatus for applying fillet material under tension to a driven roll comprising the construction defined in claim 4, in which the shiftable cam is in the form of a wedge-shaped plate extending and shiftable to and fro in the direction of the path of movement of the fillet.

EDWARD S. FLYNN.
